ROY T. AXE, OF SYRACUSE, NEW YORK, ASSIGNOR TO OLIVER M. EDWARDS, OF SYRACUSE, NEW YORK.

HINGE MECHANISM FOR RAILWAY-CAR TRAP-DOORS.

1,113,935.

Specification of Letters Patent.

Patented Oct. 13, 1914.

Application filed August 22, 1912. Serial No. 716,347.

To all whom it may concern:

Be it known that I, Roy T. Axe, of Syracuse, in the county of Onondaga and State of New York, have invented a certain new and useful Hinge Mechanism for Railway-Car Trap-Doors, of which the following is a specification.

This invention relates to trap doors for railway car platforms and particularly to the spring hinge mechanism therefor; and the invention consists in the combinations and constructions hereinafter set forth and claimed.

In describing this invention reference is had to the accompanying drawing in which like characters designate corresponding parts in all the views.

Figure 1 is a plan, partly broken away, of a trap door provided with my invention, the contiguous part of the frame of the car being also shown. Fig. 2 is an enlarged sectional view through the hinge mechanism and contiguous portion of the door. Fig. 3 is an isometric view, partly broken away, of the arbor of the mechanism, with one spring thereon.

This trap door mechanism for railway car vestibules comprises, generally, a plurality of independently acting springs for raising the door.

1 is the floor of the trap door which may be of any desirable form, size and construction.

2 is a spring barrel associated with the door.

3 is an arbor or staff forming part of the hinge mechanism, the arbor extending through the barrel 2 and being designed to be connected to the frame 4 of the car and fixed relatively thereto.

5 are coil springs on the arbor, each being connected at one end to the arbor and at its other end to the door or barrel in order to move the door in one direction.

45 As here shown the barrel 2 is formed with laterally extending flanges 6, 7 for lapsing respectively the upper and lower portions of the floor 1 of the door, these flanges 6, 7 forming between them, a channel extending substantially tangential relatively to the interior of the barrel portion 2 and open at its opposite ends or at least one end.

The arbor 3 is fixed at its ends in suitable bearings 8 and 9 fixed to the frame 4 of the car, the end 10 of the arbor in the bearing 9 being non-circular or square and fitted into a similar shaped opening in a sleeve 11 which engages directly with the barrel, the sleeve 11 having a square end 12 projecting beyond the bearing 9 in order to be engaged by a suitable tool for turning the arbor to tension the springs, the sleeve 11 turning with the arbor. When said arbor has been turned sufficiently it is held in its adjusted position by suitable fastening means as a screw 13 extending transversely through the bearing 9 and the sleeve 11.

The springs 5 are preferably helical cylindrical springs and encircle the arbor side by side, one end as 14 of each spring being bent to enter a lengthwise peripheral groove 15 in the arbor and the other end as 16 being extended laterally to enter the channel formed between the flanges 6 and 7. The radial walls of the groove 15 form abutments for corresponding ends of the springs 5.

As before stated the channel formed by the flanges 6 and 7 opens through opposite ends of the barrel and the groove 15 opens through one end of the arbor and hence the springs can be removed and inserted by an endwise sliding movement.

This hinge mechanism is particularly advantageous in that, if one or more of the springs break when the car is *en route*, the door will be raised by the remaining springs and further in that the springs are easily removed and replaced. In the trap doors now in use, when the springs become broken, the door must be lifted manually.

What I claim is:

1. A hinge mechanism for trap doors comprising a barrel, an arbor or staff extending through the barrel, and a plurality of springs movable into the barrel and onto the arbor through the same end of the barrel and being independently connected to the barrel and the arbor, substantially as and for the purpose described.

2. A hinge mechanism for trap doors comprising a barrel, an arbor or staff extending through the barrel, a plurality of springs movable into the barrel and onto the arbor

through one and the same end of the barrel, and being independently connected to the barrel and to the arbor, the springs being movable into and out of operative engagement with the barrel and the arbor by an axial movement, substantially as and for the purpose specified.

3. A hinge mechanism for trap doors comprising a barrel, an arbor or staff extending through the barrel, and a plurality of springs movable into the barrel on the arbor through one end of the barrel and being independently connected to the barrel and the arbor, the springs having a sliding and interlocking engagement with the arbor and the barrel, substantially as and for the purpose set forth.

4. A hinge mechanism for trap doors for railway car platforms comprising a fixed arbor formed with a lengthwise groove opening through one end face thereof, and a plurality of independently acting springs coiled about the arbor, each having a portion thereof bent to enter the groove, and another portion connected to the door, the springs being slideable by an endwise movement into operative connection with the arbor and the door, substantially as and for the purpose described.

5. A hinge mechanism for trap doors for railway car platforms comprising a spring barrel associated with the door and having a portion formed with a lengthwise channel extending laterally from the interior of the barrel portion thereof, and a plurality of coil springs arranged side by side in the barrel, each spring being adapted to be connected at one end to a fixed point relatively to the door and having its other end provided with an arm extending into the channel and movable therein by an endwise movement of the spring, substantially as and for the purpose specified.

6. A hinge mechanism for trap doors for railway car platforms comprising a spring barrel associated with the door, and having a portion formed with a lengthwise channel extending laterally from the interior of the barrel portion, an arbor designed to be fixed relatively to the door and the barrel and extending through the barrel, and a plurality of coil springs arranged side by side on the arbor and within the barrel, each spring having one end secured to the arbor and its other end extending into the channel, substantially as and for the purpose set forth.

7. A hinge mechanism for trap doors for railway car platforms comprising a spring barrel associated with the door and having a portion formed with a lengthwise channel extending laterally from the interior of the barrel portion, the barrel portion and the channel portion being open at corresponding ends, an arbor designed to be fixed relatively to the door and the barrel and extending

through the barrel, and a plurality of coil springs arranged side by side within the barrel, each spring having one end secured to the arbor and its other end extending into the channel, and being movable into the barrel and into connection with the arbor by an endwise sliding movement, substantially as and for the purpose described.

8. A hinge mechanism for trap doors for railway car platforms comprising a spring barrel associated with the door and having a portion formed with a lengthwise channel extending laterally from the interior of the barrel portion, an arbor designed to be fixed relatively to the door and the barrel and extending through the barrel, the arbor having a lengthwise groove opening through one end thereof, and a plurality of coil springs arranged side by side on the arbor, each spring having one end thereof bent to enter the groove of the arbor and the other end thereof arranged to enter the channel portion of the barrel, the springs being movable into engagement with the arbor and the channel portion of the barrel by an endwise movement, substantially as and for the purpose specified.

9. In combination, a trap door for railway car platforms, the same having a spring barrel along one edge thereof, the barrel having opposing flanges extending laterally from the barrel portion thereof and designed to lap upper and lower portions of the floor of the door, and to form a channel opening into the interior of the barrel portion, an arbor designed to be fixed relatively to the barrel and extending therethrough, the arbor being formed with a lengthwise peripheral groove, and a plurality of cylindrical coil springs on the arbor, each spring having one end thereof adapted to enter the groove of the arbor and the other end thereof extending laterally to enter the channel, the springs being movable into the barrel and into the arbor by an endwise sliding movement, substantially as and for the purpose set forth.

10. In combination, a barrel having an engaging surface extending substantially throughout the length thereof, a trap door associated with the barrel, bearing members, an arbor extending through the barrel and mounted in said bearing members, said arbor having a spring engaging abutment extending substantially throughout the length thereof, and a plurality of springs having corresponding ends bearing against the abutment, and other corresponding ends engaging said surface of the barrel, substantially as and for the purpose described.

11. In a car platform trap door and in combination, a barrel, an arbor or staff extending therethrough provided with an abutment and a coiled spring movable through one end of the barrel and lengthwise of the latter with one of its ends in en-

gagement with the abutment and its other end in engagement with a part of the barrel, substantially as and for the purpose described.

5 In testimony whereof, I have hereunto signed my name in the presence of two attesting witnesses, at Syracuse, in the county

of Onondaga, in the State of New York, this 9th day of August, 1912.

ROY T. AXE.
